DESIGN FOR A FRONT END HYDRAULIC LOADER

Cephas Williams, Streator, Ill.

Application October 28, 1944, Serial No. 116,020

Term of patent 7 years

(Cl. D14—3)

To all whom it may concern:

Be it known that I, Cephas Williams, a citizen of the United States, residing in Streator, in the county of La Salle and State of Illinois, have invented a new, original, and ornamental Design for a Front End Hydraulic Loader, of which the following is a specification, reference being had to the accompanying drawing forming part thereof.

Fig. 1 is a perspective view taken from a position in front and to one side of a front end hydraulic loader embodying my new design and showing the loader in a raised operating posi-

tion and attached to a conventional tractor, the dotted lines being used for illustrative purposes only;

Fig. 2 is a view similar to Fig. 1, but illustrating a different operating position of the loader; and

Fig. 3 is a top plan view of the loader shown in Figs. 1 and 2.

I claim:

The ornamental design for a front end hydraulic loader, substantially as shown and described.

CEPHAS WILLIAMS.
